FOLDING DOOR

Frederick A. Schilling, Jr., Vancouver,
British Columbia, Canada

Application December 14, 1943, Serial No. 514,257

8 Claims. (Cl. 160—213)

My invention relates to improvements in folding doors which are particularly adapted for use in hangars or other buildings where abnormally wide openings are to be provided with closures.

The objects of the invention are to provide means whereby the door when in lowered or closed position will be supported against swinging movement without having recourse to the use of door jambs, mullions or other side edge stops; to provide a structure whereby the door and parts are maintained below the lintel to which it is suspended, so that when a number of doors are used to close a wide opening such as in a hangar, no space is required between roof trusses and above the chord of the truss or lintel to accommodate any part of the door structure.

Further objects are to provide means whereby no part of the door is required to be raised above its point of suspension when being opened; to provide means whereby it can be suspended from a lintel bracketed forwardly from the main truss of the building and above the chord of said truss. Further objects are to provide a door capable of being folded into a plurality of narrow horizontal panels when in open position that the innermost part of the door is only a short distance from the entrance opening. This narrow width of the opened door makes it possible for heating devices, lighting equipment and particularly the monorail hoisting equipment to be placed well forward of the building and facilitates the repairing and servicing of planes close to the closed doors. Furthermore, since the door support or lintel can be bracketed out from the front side of the front truss and be carried above its chord when in open position the chord of all the trusses can be three or more feet lower than is possible with other types of suspended doors, thus saving a similar height in the finished building, reducing wind stresses on walls and structural stresses on columns etc. and effecting appreciable saving in the cost of construction of the building.

The invention contemplates a door formed of a plurality of hinged panels and a truss for stiffening and holding said panels in a single plane when lowered to closed position, as will be more fully described in the following specification and shown in the accompanying drawings, in which:

Fig. 1 is an inside elevational view of the invention.

Fig. 2 is a section taken on the line 2—2 of Figure 1.

Fig. 3 is an inside elevational view showing the door partly raised.

Fig. 4 is a sectional view taken on the line 4—4 of Figure 3.

Fig. 5 is a transverse view of the door in raised position.

Fig. 6, 7 and 8 are detail views of the trusses and interconnecting spreaders.

Fig. 9 is a sectional view taken on the line 9—9 of Figure 1.

Fig. 10 is a detail view of the suspension cable receiving bracket.

In the drawings like characters of reference indicate corresponding parts in each figure.

The numeral 1 indicates the sides of an opening, 2 a lintel over the opening and 3 the ceiling or roof structure substantially level with the underside of the lintel.

The numeral 5 indicates generally a door which is made up of panels 6 which are hinged together with hinges 7 and 8, the hinges 7 connecting a pair of adjacent panels and being on the inside of the door and the hinges 8 connecting adjacent panels and being on the outside of the door, so that the panels will fold together in zig zag fashion.

The uppermost panel 6 is hung from the lintel 2 with a hinge 9 secured to the outside of the door. Extending rearwardly from the upper extremity of the door and level with the hinge 9 is a pair of spaced shafts 11 which are rockingly mounted below the ceiling 3 or any convenient roof structure. From each shaft 11 is a cantilever truss generally indicated by the numeral 12 and which consists of truss sections 13, 14, 15 and 16 connected together by hinge pins 18. The sections 14 and 15 are twice the length of the sections 13 and 16 and are each pivotally mounted on a shaft 20, which in turn is swingingly mounted on a hinge 21 secured to a door panel 6, see detail in Figures 6, 7 and 8.

The shafts 20 extend beyond the outer member of their respective truss members 14, 15 and 16 and each pair is connected together by a spreader 22 which serves to keep said shafts at right angles to the joint between adjacent door panels 6 during the initial opening movement and also to stiffen the trusses.

One or more suspension cables 25 extending downwardly from suitable hoisting machinery, not shown, are attached at their lower ends to the lower ends to the lowermost panel 6 of the door as at 26 and in order to facilitate the breaking of the joints of the door at the commencement of its collapsing movement spring brackets generally indicated by the numeral 28, see detail in Figure 10, are provided, these brackets are

each provided with a U-shaped jaw 29 at their upper extremity through which a portion of a suspension cable 25 passes when the door is in closed and partly closed position. The projection of the jaws 29 is such that when the cable is free from lifting strain, as when the door is closed, the cable is thrust inwardly of the building and out of alignment as shown in Figure 9, so that the initial lifting strain will slightly tend to straighten the bracket 28 and its inherent spring tension will throw the adjacent hinges 7 outwardly thus starting the collapse or folding movement of the door. As a means of counter-weighting the panels 6 when they are being carried forwardly of the hinges 8 counterweights 30 carried upon arms 31, see Figures 1, 3, 4, 5 and 9, are provided, which are secured to the inner side of the panels 6 immediately above its hinges 8.

Obviously when the trusses 12 are fully extended in a vertical position as when the door is closed, they will afford a support to the door against either inward or outward pressure and any thrust inwardly or outwardly on the door will be transmitted to the shafts 11 which in effect become abutments or bases for the trusses 12 against the ceiling or other structure to which the spaced shafts 11 are mounted.

Since no side stationary jambs or side edge supports are necessary for the door, hanger or other wide openings can be effectively closed by a plurality of similar doors all set with adjacent side edges substantially in contact with each other and said doors may be opened separately or collectively as desired, leaving one totally unobstructed opening.

What I claim as my invention is:

1. A folding door adapted for hanging from one edge, said door comprising a plurality of horizontal panels hingedly connected together along their abutting edges, a truss extending across some of the panels adapted to hold said panels in a single plane when in closed position, said truss being made up of hinge jointed sections, some of said sections being connected to some of the panels.

2. A folding door adapted for hanging from one edge, said door comprising a plurality of horizontal panels hingedly connected together along their abutting edges, a truss extending across some of the several panels adapted to hold said panels in a single plane when in closed position, said truss being formed of hinge jointed sections, some of said sections being connected to some of the panels and adapted to be connected to a stationary part adjacent one edge of the door.

3. A folding door adapted for hanging by one edge, from a stationary part adjacent said edge, said door comprising a plurality of panels hingedly connected together adjacent their abutting edges, a truss extending across the panels at a right angle to their abutting edges, said

truss being formed of hinge jointed sections and adapted to fold coincidentally with the folding of the door, said truss sections standing when in extended position in a plane perpendicular to the plane of the door.

4. A folding door adapted for hanging by one edge from a stationary part adjacent said edge, said door comprising a plurality of panels hingedly connected together adjacent their abutting edges, a truss extending across said panels, said truss being formed of hinge jointed sections, some of said sections being mounted on shafts extending perpendicularly from the plane of the door, said shafts being hingedly connected at one end to some of the panels.

5. A folding door adapted for hanging by one edge from a stationary part adjacent said edge, said door comprising a plurality of panels hingedly connected together adjacent their abutting edges, a truss extending across said panels, said truss being formed of hinge jointed sections, some of said sections being mounted on shafts extending vertically from the plane of the door, said shafts being hingedly connected at one end adjacent an edge of some of the panels.

6. A folding door adapted for hanging by one edge from a stationary part adjacent said edge, said door comprising a plurality of panels hingedly connected together adjacent their abutting edges, a truss extending across said panels, said truss being formed of hinge jointed sections, some of said sections being mounted on shafts extending vertically from the plane of the door, said shafts being hingedly connected at one end to some of the panels, and a shaft adapted to be fixed to said stationary part and one of said truss sections being connected to said shaft.

7. A folding door adapted for hanging by one edge from a stationary part adjacent said edge, said door comprising a plurality of panels hingedly connected together adjacent their abutting edges, a truss extending across said panels, said truss being formed of hinge jointed sections, some of said sections being mounted on shafts extending vertically from the plane of the door, said shafts being hingedly connected at one end adjacent an edge of some of the panels, and a shaft adapted to be fixed to said stationary part and one of said truss sections being connected to said shaft.

8. A folding door adapted for hanging from one edge to a stationary part adjacent said edge, said door comprising a plurality of hinge connected panels, a pair of trusses extending across the hinge line of said panels, said trusses being formed of hinge connected sections, some of said sections being mounted on shafts extending perpendicularly from the plane of the door and a spreader connecting a shaft of one truss to a shaft of another truss.
